(57) **CLAIM**

The ornamental design for a fork lift, as shown and described.

DESCRIPTION

FIG. 1 is a left side view of a fork lift showing my new design;

FIG. 2 is another left side view thereof;

FIG. 3 is a right side view thereof;

FIG. 4 is another right side view thereof;

FIG. 5 is a front view thereof;

FIG. 6 is a rear view thereof;

FIG. 7 is a top view thereof;

FIG. 8 is a bottom view thereof;

FIG. 9 is a front perspective view thereof; and,

FIG. 10 is a rear perspective view thereof.

The broken lines in the drawings are to show portions of the fork lift which form no part of the claimed design.
